UNITED STATES PATENT OFFICE.

CHARLES L. BRALEY, OF CINCINNATI, OHIO, ASSIGNOR TO THE AMERICAN LAUNDRY MACHINERY COMPANY, OF CINCINNATI, OHIO, A CORPORATION OF OHIO.

PRESSING-MACHINE.

1,397,202.

Specification of Letters Patent. Patented Nov. 15, 1921.

Application filed December 18, 1916. Serial No. 137,600.

To all whom it may concern:

Be it known that I, CHARLES L. BRALEY, citizen of the United States, residing at Cincinnati, in the county of Hamilton and State 5 of Ohio, have invented certain new and useful Improvements in Pressing-Machines, of which the following is a specification.

This invention relates to pressing machines, and more particularly to machines 10 for pressing garments, textile or other fabrics. The object of the invention is to provide improved vacuum means for withdrawing from the pads of the pressing member, from the space between said pads, and 15 from the garment or fabrics being pressed any steam, vapor, moisture or water thereon, said means being connected to operate conjointly with the device for applying steam to the garment or fabric for the pressing 20 operation. More specifically the object of the invention is to provide an improved pressing machine whose lower pressing member is so arranged that the operator can direct steam therefrom upon the garment or fabric or can withdraw through 25 said member the steam, vapor or moisture. A further object of the invention is to provide an improved pressing machine embodying means for applying steam to the garment and means for withdrawing the steam, 30 vapor and moisture, said two means being operable from the same controlling device, and preferably in such manner that either of said means can be rendered effective, when 35 desired, the other means being simultaneously rendered ineffective.

Further objects of the invention are in part obvious and in part will appear more in detail hereinafter.

40 Referring to the drawings, Figure 1 is a side elevation illustrating the application of the invention to one form of pressing machine; Fig. 2 is a plan view, partly in section on the line 2-2, Fig. 1; Fig. 3 is 45 a detail section on the line 3-3, Fig. 2, showing the steaming valve; Fig. 4 is a broken out plan view of the lower pressing member; Fig. 5 is a longitudinal section on the line 5-5, Fig. 4; and Fig. 6 is a cross 50 section on the line 6-6, Fig. 4.

The invention may be applied to any desired form of pressing machine, but in the drawings, for purposes of illustration, has been shown applied to a pressing machine 55 of the general form shown in my prior ap-

plication for pressing machine, filed Aug. 14, 1916, Serial No. 114,794. For clearness of illustration the main parts of the machine have been shown in dotted lines, the full lines representing the parts more immediately concerned in the present invention.

The machine shown comprises a suitable frame 1 supporting the lower pressing member or bed 2 and having a swinging arm or lever 3 on which is located the coöperating upper pressing member or head 4. Said two pressing members are moved toward and from each other for the pressing operation by swinging movement of said lever, 70 as will be readily understood.

The lower pressing member, shown in Figs. 4, 5 and 6, comprises a hollow body 5 having an inner steam heating chamber 6 supplied with steam from pipe 7 circulated through said chamber to the outlet pipe 8. The bed usually has a slight turning movement on the frame to accommodate itself to the head, the axis of turning movement in this case being the axis of the pipes 80 7 and 8. Above chamber 6 is a horizontal wall 9 separating said chamber from a shallow space or chamber 10 between wall 9 and a thin metal plate 11 having a large number of small perforations 12 and above 85 which is the padding 13.

Chamber 10 serves two purposes. First, it is a steam discharge chamber from which steam is supplied through the perforated plate and padding to the garment or fabric 90 lying upon the bed, and, second, it serves as a vacuum chamber through which the steam, vapor and moisture are withdrawn. For these purposes it is connected both to a steam supply and to a source of vacuum. 95

The chamber 10 shown has a number of radiating or diverging ribs 14 to support plate 11. The channels between said ribs lead to one or two openings 15 communicating by lateral passages 16 with a pipe 17 100 connected to a pipe 18 extending downwardly to a suitable source of suction, such as the inlet side of the centrifugal pump 19 driven by a power source, for example, the electric motor 20. In pipe 18 is a suitable valve 21 having a sliding valve stem 22 which opens the valve when pulled out and closes it when pushed in. The motor and pump run constantly so that whenever valve 21 is open suction or vacuum is effective in 110

chamber 10 and any steam, vapor or moisture on the garment or in the pads or the space between said pads is withdrawn through chamber 10 and discharged 5 through the pump. 23 indicates a pipe or conduit communicating by way of the valve 24 with the pipe 18 leading to the cavity 10. This pipe 23 may communicate with any suitable source of steam supply, and in 10 the drawings is shown as communicating with the live steam space or heating chamber 6. Valve 24 is provided with a rod 25 connected to a link 26 which is supported by a stationary rod 27, the valve 24 being normally held closed by a spring 28.

The operating mechanism for the two valves 21 and 24 is so arranged that either one may be opened to render either steam or vacuum effective in chamber 10, the arrangement being preferably such that when one valve is opened the other is closed and vice versa. As shown the operating mechanism comprises a bell crank lever having a foot treadle 29 and an arm 30 connected to a link 31 whose free end has a lateral projection 32 surrounding steam valve stem 22 in advance of a collar 33 adjustable on said stem and secured thereon by a set screw 34. Collar 33 carries a depending weight 35, and as the valve stem is horizontal, said weight applies lateral bending movement to the valve stem sufficient to prevent the valve from crawling from any position in which it may be and thereby disturbing its setting. Link 31 is moved rearwardly (to the left in Fig. 1) by a spring 36 to open the vacuum valve. When said link is moved in the opposite direction it first closes the vacuum valve and then compresses a spring 37 housed in a chamber 38 of the projection 32 and abutting a collar 39 on the valve stem. This construction provides lost motion between the link and vacuum valve so that the first motion of the link may be utilized to close the vacuum valve and its further motion to open the steam valve. Said steam valve is opened by a lateral projection 40 on link 31 which engages an arm 41 on member 26 when the link is pulled forwardly by the bell crank lever. If the operator desires to apply steam to the padding or garment he may do so by depressing the treadle 29, which closes the vacuum valve 21 and opens 55 the valve 24, thereby permitting the passage of live steam from the space 6 through the pipe 23, through the steam valve 24 to that part of the pipe line 18 which is above the valve 21. This valve 21 being closed at this time, the steam rises through the pipe 18 to the chamber 10 and through the padding.

The construction described is simple and can be readily applied to any form of pressing machine. It puts both the steaming device and vacuum attachment under the con-

trol of the operator, who, by the operation of a single device can secure either effect at will. Other advantages will readily occur to those skilled in the art.

What I claim is:—

1. A pressing machine, comprising relatively movable pressing members, means for supplying steam to the space between said members, means for producing a flow of air to remove steam and moisture from said members and the space therebetween, and a single controlling device for both said means.

2. A pressing machine, comprising relatively movable pressing members, means for supplying steam to the space between said members, means for producing a flow of air to remove steam and moisture from said members and the space therebetween, and means operable in one direction for rendering one of said means effective and in another direction for rendering the other means effective.

3. A pressing machine, comprising relatively movable pressing members, means for supplying steam to the space between said members, means for producing a flow of air to remove steam and moisture from said members and the space therebetween, an operating device having two positions for rendering either of said means effective, and yielding means normally maintaining said device in one of said positions.

4. A pressing machine, comprising relatively movable pressing members, means for supplying steam to the space between said members, means for producing a flow of air to remove steam and moisture from said members and the space therebetween, valve means for controlling the flow of air, valve means for controlling the supply of steam, and a single operating device for said valve means.

5. A pressing machine, comprising relatively movable pressing members, one of which is provided with a hollow chamber opening through its face, means for supplying steam to the space between said members, means connecting said chamber to a source of suction, and a single means for rendering effective either said steam supply or source of suction.

6. A pressing machine, comprising relatively movable pressing members, one of which is provided with a hollow chamber opening through its face, a source of steam supply, a source of suction, and means arranged when operated to establish communication from either of said sources of steam or suction to said chamber.

7. A pressing machine, comprising relatively movable pressing members, one of which is provided with a hollow chamber opening through its face, a pipe connecting said chamber to a source of suction and pro-

vided with a valve, a source of steam supply, and means for operating said valve arranged when said valve is closed to establish communication from said steam supply to said

5 chamber.

8. A pressing machine, comprising relatively movable pressing members, one of which is provided with a live steam space and a hollow chamber opening through its 10 face, a valve controlling the flow of steam from said space to said chamber, a source of suction, and means for operating said valve arranged when said valve is closed to establish communication from said suc-

15 tion source to said chamber.

9. A pressing machine, comprising relatively movable pressing members, one of which is provided with a live steam space and a hollow chamber opening through its 20 face, a pipe connecting said space to said

chamber, suction producing means also connected to said pipe, and means for rendering either steam or suction effective in said chamber.

10. A pressing machine, comprising relatively movable pressing members, a source of suction, a source of steam supply, a valve controlling the flow of steam from said source of steam to the space between said members, a valve arranged when opened to render said suction source effective in said space, and a lever for operating both valves, having a lost motion connection with one thereof.

In testimony whereof I affix my signature.

CHARLES L. BRALEY.
